UNITED STATES PATENT OFFICE.

WILLIAM P. CASHEN, OF LINCOLN, ILLINOIS.

SPRAYING APPARATUS.

1,159,829.

Specification of Letters Patent.

Patented Nov. 9, 1915.

Application filed September 9, 1914. Serial No. 860,877.

To all whom it may concern:

Be it known that I, WILLIAM P. CASHEN, a citizen of the United States, residing at Lincoln, in the county of Logan and State 5 of Illinois, have invented a Spraying Apparatus, of which the following is a specification.

The primary object of my invention is to provide a spraying apparatus especially 10 adapted for use in coal mines, by which a liquid preparation, as lime-water, may be sprayed in the tunnels of the mine to allay dust and thereby not only purify the air but minimize the danger of explosions and fire; 15 the discharge of the several spraying nozzles being such as to thoroughly cleanse the air of combustible material as well as cover the side walls and top with a preservative liquid which will render the woodwork in 20 the tunnel non-combustible.

A further object of my invention is to provide an apparatus of this character which may be run on the tracks used by the coal cars in conveying the coal to the shaft, and 25 which may be operated at comparatively little expense.

Other objects and advantages of my invention will hereinafter appear, and what I claim as new, and desire to secure by Letters- 30 Patent, is more specifically set forth in the appended claims.

In the accompanying drawings, which form a part of this specification: Figure 1 is a side elevation, illustrating a spraying apparatus constructed in accordance with my invention. Fig. 2 is an end view thereof. Fig. 3 is a top plan view. Fig. 4 is a detail sectional view, on a line directly in the rear of the air-pumps, to more clearly show said 35 air-pumps and connections. Fig. 5 is a detail view of the supporting frame for the air-pumps and operating mechanism thereof. Fig. 6 is a detail view showing a modification.

Like numerals of reference indicate like parts in all the figures of the drawings.

In carrying out my invention I provide a large closed tank 6, preferably made of boiler iron and cylindrical in shape, with 40 the heads 7, 7, securely riveted to the body, as customary in tanks of this general character. In the present instance the tank is mounted on a suitable wheeled truck, comprising longitudinal beams or sleepers 8, 8, 45 resting on the axles 9, 9, of the track-wheels

10, said beams or sleepers being connected near their ends by iron bars 11, 11, and 12, arranged in pairs; the ends of the bars of each pair embracing the upper and lower edges of the beams, to which they are bolted, 60 and the upper bar curved downwardly between the beams corresponding with the curve of the cylindrical tank so that the latter may seat securely on the truck. The truck is provided with a suitable coupling 65 or draw-bar 13, at its ends, for connecting the same to a coal-car or other means for pulling it along the track laid in the tunnel for the coal cars to run upon.

The tank 6 is securely held upon the truck 70 by means of iron bands or straps 14, 14, secured at their lower ends to the beams 8, and connected at the upper side of said tank by clamping-bolts 15, and to these iron bands or straps the frame for supporting the air-pump and its operating mechanism is attached, as hereinafter described.

The tank 6 is intended to contain any liquid preparation or solution suitable for allaying and preserving combustible dust 80 such as usually collects in coal mines and saturating wood-work to make it fire-proof, and for the purpose of spraying this liquid in the most effective manner there is located at the lower end of one of the heads 7 an 85 outlet pipe 16, having a valve 17, and connecting with a plurality of discharge pipes 18 terminating in nozzles 19 of any approved pattern. In the present instance there are three discharge pipes, one disposed 90 vertically so that the nozzle thereof will throw a spray upwardly and upon the ceiling or top of the tunnel, and opposite laterally disposed discharge pipes the nozzles of which spray in opposite directions toward 95 the sides and portions of the bottom of the tunnel. In this manner, as will be readily seen, the entire air space of the tunnel will be sprayed or thoroughly washed and sufficient of the liquid preparation or solution 100 deposited on the wood-work of the tunnel to preserve it and prevent it from catching fire.

In order to force the liquid contents of the tank out of the discharge nozzles with 105 sufficient force to provide the necessary spray I provide air-pressure in said tank by means of a pair of air-pumps 20, 20 arranged on a line with each other and having their piston-rods 21 connected to a wrist- 110

wheel 21^a on one end of a driving-shaft 22, the latter being driven from one of the track-wheels 10 by a sprocket chain 23 passing over sprocket-wheels 24 and 25, connected to said shaft and sprocket-wheel, respectively. The sprocket-wheel 24 is loose on the shaft and has a clutch-member 26 for slidable engagement with a companion clutch-member 27 fixed to the shaft, and this 10 clutch is thrown in and out of engagement by means of a lever 28, supported in the manner hereinafter described.

The air-pumps discharge into pipes 20^a, 20^b, respectively, which are connected to a 15 pipe 29, extending into the tank, and through which the air under pressure from the pumps is led to the tank; a predetermined maximum air-pressure in said tank being maintained by the employment of a 20 safety-valve 30, of any approved pattern.

The air-pumps and driving shaft are carried by an iron yoke 31, mounted on a supporting-frame at one side of the upper part of the tank and secured to the holding straps 25 14. This supporting frame consists of an iron-plate 32, a V-shaped flat bar 33, bolted at its ends to the end portions of said plate, and a V-shaped flat bar 34, bolted at its angle portion to the angle portion of the aforesaid bar by the bolts, as 35, which secure the supporting-yoke 31 to the supporting-frame, said yoke being supported in proper horizontal alinement above the frame by interposed sleeves 36. The supporting-frame is braced by a V-shape bar 37, bolted to the frame bars 33 and 34, and said bar 37 serves also as a fulcrum for the lever 28, hereinbefore referred to. Additional brace-bars, 38, connect the frame bars, as shown in 35 the drawing, and one of these brace-bars is provided with recesses, as 38^a and 38^b with which the operating-lever 28 engages for holding the clutch in or out of operative engagement, according to the position of the 40 lever, as will be understood. The ends of the plate 32 and frame-bar 34 are apertured, as at 32^a and 34^a, respectively, to receive the ends of the bolts 39 and 40 projecting from the tank or holding-straps 14, and upon 45 which nuts 41 are threaded for attaching the frame to said tank. In this manner, as will be readily seen, the holding straps, frame, and parts carried thereby, may be conveniently removed from the tank, thus permitting the parts mentioned to be applied to 50 any tank in the form of an attachment.

It will be noted that the handle of the lever for operating the clutch is located beyond the opposite end of the tank from the 55 spraying-nozzles, so that the operator may be out of the way of the spraying liquid, and in order that the spraying of the liquid may be regulated, or cut off by the operator conveniently at any time, the valve or cut-off 60 17 is provided with a rod 42, supported by a

bracket-arm 43 projecting from the tank, the rod 42 having a crank 44 to which is attached a pulling-rod 45 terminating in its outer end in a loop or handle 46 by which it is manipulated, said loop or handle being 70 located adjacent the operating end of the lever 28. The outer end of this pulling-rod is supported by a link 47, attached to and extending from a part of the apparatus for the purpose.

In the modification Fig. 6 a transmitting gear is interposed between the driving-shaft 22 and wrist-wheel 21, and in this instance a sprocket-wheel 50 is mounted on the inner end of shaft 22 and connected by chain-belt 80 51 to a sprocket-wheel 52 on an auxiliary shaft 53, the latter being connected to drive the wrist-wheel by sprocket-wheel 54, chain-belt 55 and sprocket-wheel 56, the latter being fixed on a stub-shaft 57 carrying said 85 wrist-wheel.

Having fully described the construction of my improved spraying apparatus, the operation of the same will be readily understood from the accompanying drawings, for in 90 practice the truck carrying the tank with its spraying nozzles and air-pumps, will be attached to a coal-car so as to be drawn through the mine thereby, or it may be drawn independently if desired, and as the 95 truck-wheel 10 carrying the sprocket-wheel 25 is revolved by the movement of the truck the chain 23 will turn the sprocket-wheel 24, and the engaging clutch connecting said sprocket-wheel with the driving-shaft 22 100 will turn the latter thus operating the air-pumps 20, 20, to produce the required air-pressure in the tank, which will force the liquid contents out of the nozzles in a plurality of sprays reaching all parts of the 105 mine or tunnel as the apparatus passes therethrough. The air-pressure in the tank is limited by the safety-valve, and the spraying of the liquid regulated by operating the cut-off valve through the intervention of the 110 pulling-rod 45. In transporting the apparatus from place to place, or at any other time, the spraying may be cut off by operating the valve 17, and the air-pumps thrown out of operation by operating the lever 28 115 to disengage the clutch.

The nozzles employed may be, and preferably are, of the adjustable type, permitting the volume or character of the spray to be changed by turning the cap, and in practice 120 I prefer that the nozzles at the ends of the lateral discharge pipes be connected thereto by universal-joints 48, so that said nozzles may be turned and change the direction of the spray, according to the size of the tunnel 125 or mine.

Though I have described my invention or spraying apparatus as used for the purpose of spraying mines, it will be understood, of course, that it may be used for the purpose 130

of spraying trees, shrubbery, &c., and in this instance ordinary ground-wheels would be applied to the truck in place of track-wheels.

Having described my invention, I claim:

- 5 1. In a spraying apparatus for the purposes set forth, the combination with a wheeled truck, of a tank mounted horizontally thereon, and discharge nozzles at the lower part of the tank for spraying the contents thereof; together with holding straps secured to the truck and embracing the tank, a supporting-frame bolted to the straps, air-pumps mounted on the supporting-frame and connected to the tank for forcing air 10 into the same, and means for operating the air-pumps from the wheels of the truck, substantially as shown and described.
- 15 2. In a spraying apparatus for the purposes set forth, the combination with a wheeled truck, of a tank mounted horizontally thereon, spraying nozzles at the lower end of the tank for discharging the contents thereof, holding straps secured at their ends to the truck and embracing the tank, and 20 bolts projecting from said holding straps; together with a supporting-frame made up of metal bars apertured at their ends to receive the aforesaid bolts, air-pumps mounted on the frame and connected to the tank 25 for forcing air into the same, a safety-valve for limiting the maximum pressure in the tank, and means for driving the air-pumps from the wheels of the truck, substantially as shown and described.
- 30 3. In a spraying apparatus for the purposes set forth, the combination with a wheeled truck, of a cylindrical tank mounted horizontally thereon, spraying nozzles connected to the tank for discharging the 35 contents thereof, holding straps secured at their ends to the truck and embracing the tank, bolts projecting from the holding straps, and a supporting-frame removably connected to the tank and comprising a plate 40 having apertures at its ends, a V-shape bar 45
- attached at its ends near the ends of said plate, and a second V-shape bar attached at its angle to the angle of the other frame-bar and having apertures at its ends, the aforesaid apertures of the plate and frame-bar 50 receiving the bolts projecting from the holding-straps to secure said frame to the tank; together with air-pumps secured upon the supporting-frame, a driving-shaft for the air-pumps also mounted on the frame, and 55 means for operating the shaft from one of the wheels of the truck, substantially as shown and described.
4. In a spraying apparatus for the purposes set forth, the combination with a wheeled truck, of a cylindrical tank mounted horizontally thereon, spraying nozzles connected to the tank for discharging the contents thereof, metal holding straps secured at their ends to the truck and embracing the tank, bolts projecting from the holding straps, and a supporting-frame removably connected to the holding-straps and comprising a plate having apertures at its ends, a V-shape bar attached at its ends to 60 the end portions of said plate, a second V-shape bar attached at its angle to the angle of the other frame-bar and having apertures at its ends, and brace-bars connecting the ends of one V-shape frame-bar to the other, 65 the aforesaid apertures in the plate and frame-bar receiving the bolts projecting from the holding-straps to secure said frame to the tank; together with air-pumps secured on the supporting-frame, a driving-shaft for the air-pumps also mounted on the frame, a clutch and sprocket-wheel on the driving-shaft, and a sprocket-chain for driving the sprocket-wheel from an axle of the truck, substantially as shown and described. 70
- 75 5. In a spraying apparatus for the purposes set forth, the combination with a wheeled truck, of a cylindrical tank mounted horizontally thereon, spraying nozzles connected to the tank for discharging the contents thereof, holding straps secured at their ends to the truck and embracing the tank, bolts projecting from the holding straps, and a supporting-frame removably connected to the tank and comprising a plate having apertures at its ends, a V-shape bar 80
- 85
